UNITED STATES PATENT OFFICE

CHARLES P. FENLON, OF NEW YORK, N. Y.

DESIGN FOR A TEXTILE FABRIC OR SIMILAR ARTICLE

Application filed June 6, 1930. Serial No. 35,948. Term of patent 7 years.

To all whom it may concern:

Be it known that I, CHARLES P. FENLON, a citizen of the United States of America, residing at New York, in the county of New York and State of New York, have invented a new, original, and ornamental Design for Textile Fabric or Similar Article, of which the following is a specification, reference being had to the accompanying drawing, forming part thereof.

The figure of the drawing is a plan view of a piece of textile fabric or similar article, showing my design, a repeat unit of which is embodied in the area outlined by dot and dash lines. Such unit is repeated over the surface of the fabric in the relation indicated by the extension beyond the dot and dash lines.

I claim:

The ornamental design for a textile fabric, or similar article, as shown and described.
